G. W. CALDWELL

By *Watson E. Coleman*

Attorney

UNITED STATES PATENT OFFICE.

GILBERT W. CALDWELL, OF GAY, GEORGIA.

SEPARATOR.

1,157,756.

Specification of Letters Patent.

Patented Oct. 26, 1915.

Application filed June 12, 1915. Serial No. 33,783.

To all whom it may concern:

Be it known that I, GILBERT W. CALDWELL, a citizen of the United States, residing at Gay, in the county of Meriwether and State of Georgia, have invented certain new and useful Improvements in Separators, of which the following is a specification, reference being had to the accompanying drawings.

10 This invention relates to certain improvements in separators and has relation more particularly to a device of this general character especially designed and adapted for use in connection with cotton seed; and 15 it is an object of my invention to provide a separator of this general character having novel and improved means whereby black or faulty seeds together with all dirt and loose linters may be separated from the 20 planting seeds.

The invention consists in the details of construction and in the combination and arrangement of the several parts of my improved separator whereby certain important advantages are attained and the device is rendered simpler, less expensive and otherwise more convenient and advantageous for use, all as will be hereinafter more fully set forth.

30 The novel features of the invention will be carefully defined in the appended claim.

In order that my invention may be the better understood, I will now proceed to describe the same with reference to the accompanying drawings, wherein—

Figure 1 is a substantially longitudinal vertical sectional view taken through a separator constructed in accordance with an embodiment of my invention; Fig. 2 is a 40 transverse vertical sectional view taken through the device as herein disclosed and through the discharging extremity of the screen element; and Fig. 3 is an end elevational view of the device as herein set forth.

45 As disclosed in the accompanying drawings, 1—1 denote end panels having their adjacent extremities connected by the plates 2 and 3, the lower plate 2 having coacting therewith and with the end panels 1, the 50 side panels 4 whereby a trough is afforded to receive the faulty seeds or the like after being separated and one of the end panels 1 at its lower extremity is provided with an opening 5 whereby the material collected 55 within the trough may be readily removed when required.

The opposed faces of the panels 1 adjacent their upper extremities are provided with the supports 6 with which are engaged the extremities of the perforate screen 7 preferably formed of reticulated material of predetermined mesh and of semi-circular formation in cross section, said screen being disposed longitudinally on a predetermined incline with its lower end portion 65 provided with the laterally disposed extension 8 also preferably formed of reticulated material and coacting with the adjacent end panel 1 to afford a discharge spout for the 70 planting seed.

The upper plate 2 adjacent the elevated extremity of the screen is provided with a feed opening 9 surrounded by a hopper 10 of desired dimensions and into which the seeds to be separated are initially deposited 75 as required. Operatively supported by the end panels 1 and disposed through the chamber afforded by the screen 7 is the shaft 11, the opposite extremities of which extend exteriorly beyond the end panels 1, one 80 of said extremities having secured thereto a balance wheel 12 while the opposite extremity is operatively engaged, as at 14, with a suitable source of power, said power being herein disclosed as a manually operated drum 15 engaged with the shaft 11 through the medium of a belt 16. I wish to state, however, that it is not my desire 85 to limit myself to any specific means for imparting the requisite axial rotation to the 90 shaft 11.

The shaft 11 intermediate the panels 1 and substantially entirely bridging the space between said panels has affixed thereto a drum or roller 17 from which radiate the 95 spirally arranged fingers or blades 18 which serve to assure the requisite travel of the seed to be separated downwardly over the screen 7 to the discharge spout thereof and, as is believed to be self-evident, said fingers 100 or blades 18 also serves as an agitating means for the seed whereby the effected separation thereof is facilitated. I also find it of advantage to connect the upper side margins of the panels 1 by the strips 19 and to which is directly secured the longitudinal margins of the screen 7. I also find it of advantage to provide the end panels 1 with the supporting members 20 whereby the same may be effectively maintained in 110 an operative position.

From the foregoing description, it is

thought to be obvious that a separator constructed in accordance with my invention is of an extremely simple and comparatively inexpensive nature and is particularly well 5 adapted for use by reason of the convenience and facility with which it may be assembled, and it will also be obvious that my invention is susceptible of some change and modification without material departure 10 from the principles and spirit thereof and for this reason I do not wish to be understood as limiting myself to the precise arrangement and formation of the several parts herein shown in carrying out my invention in practice.

I claim:

A device of the class described comprising a trough, including end panels extending above the trough proper, one of said

end panels having an opening therein to 20 afford a communication within the trough, a screen element of semi-circular formation and bridging the space between the upper portions of the end panels, a lateral extension carried by the screen element and co-acting with an end panel to afford a discharge chute, said screen element being disposed on an incline with the discharging spout thereof at its lower extremity, and agitating means coacting with the screen 30 element.

In testimony whereof I hereunto affix my signature in the presence of two witnesses.

GILBERT W. CALDWELL.

Witnesses:

J. R. GAY,
S. M. SMITH.
